CLAIM

(**) Term: **14 Years**

The ornamental design for a front panel for an electronic device, as shown and described.

DESCRIPTION

FIG. 1 is a front perspective view of a front panel for an electronic device in accordance with our design;

FIG. 2 is a front elevational view thereof;

FIG. 3 is a top view thereof;

FIG. 4 is a bottom view thereof; and,

FIG. 5 is a left side view thereof, the right side being a mirror image of the left side.

The broken lines provided in the above views are used to indicate environmental structure and form no part of the design.
